CLAIM

The ornamental design for a shirt with pocket, as shown and described.

DESCRIPTION

FIG. 1 is a rear perspective view of a first embodiment of a shirt with pocket showing my new design;

FIG. 2 is a front view thereof;

FIG. 3 is a rear view thereof;

FIG. 4 is a left end view thereof, the right end view being a mirror image of the left end view;

FIG. 5 is a top view thereof; and,

FIG. 6 is a bottom view thereof.

The small dot, small dot lines on the pocket of the shirt with pocket in FIGS. 1-5 represent stitching and are part of the claimed design.

The large dash, large dash broken lines in the shirt with pocket in FIGS. 1-6 represent an electronic device and earphones, collar, sleeves, and tail of the shirt which are immediately adjacent to claimed surfaces, represent the bounds of the claimed design, while all other broken lines are directed to the environment and are for illustrative purposes only; the broken lines form no part of the claimed design.
